5 Claims. (Cl. 214—8.5)

The present invention relates to a device for feeding compression molds for cigar fillers either to a machine which fills the molds or to a machine which removes compressed fillers from the molds. The molds which are fed are of the well known type comprising a plate having a series of molding chambers.

An object of the invention is to provide feeding means in which a series of superposed molds is fed smoothly and without danger of jamming and also without undue disturbance of tobacco which may be in the molds.

Another object is to accomplish the feeding of the lowermost mold to a position in which it may readily be seized by the device for withdrawing the mold from the stack.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a side elevation of the feeding device as applied on an end of a cigar machine.

Figure 2 is a plan view of the same device.

Figures 3 to 6 are detail views of the feeding mechanism showing the cycle of feeding one mold.

Referring to Figures 1 and 2 the invention is shown as applied to a cigar machine which may be either the machine for placing tobacco in the compression chambers of the molds or the machine for removing the finished cigars therefrom. The machine has a table 12 upon one end of which the feeding device is supported from a bracket 21. The feeding device consists in obliquely disposed guides 1 which are spaced apart and have side portions extending laterally of the molds and connecting portions which are inclined at substantially the angle of the bevels 2 at the ends of the molds 3. The beveled end 2 of the mold 3 rests then upon the connecting portion of the rear guide 1 which is at the left hand in Figure 1. This relation of guides and molds disposes a stack of molds in longitudinally offset superposed relation. The forward edge of a lower mold is in position advanced beyond the forward edge of an overlying mold.

Each of the molds 3 is provided in its upper face near one end with a notch 5. The molds shown are made symmetrically in that both front and back edges are provided with notches, bevels and a stepped portion later to be described. The machine for handling the molds

has a device for removing the lowermost from the said stack. This device consists in an arm 11 which has at one end a finger 6 which can dip into the notch 5 of the lowermost mold for the purpose of withdrawing this mold from the stack. The arm 11 is pivoted to the upper arm of a bell crank lever 10 which in turn is pivotally mounted at 9 upon the frame of the machine. The lower arm of the bell crank lever 10 is connected to the connecting rod 8 which is secured to the crank pin 22 on the driven wheel 7. Rotation of the wheel 7 then produces reciprocation of the finger 6. The finger 6 and the arm 11 must execute a slight movement in the vertical plane in addition to the reciprocating movement in order to engage in the notch 5 of a mold, which movement may be effected by any well known means (not shown) and not forming any part of the present invention.

The guides 1 have the further constructional features now to be described. The guide 1 at the feeding side of the stack has its end turned at 13 in Figure 1 to a substantially vertical position. Therefore a mold in the lowermost position has the notch 5 uncovered to permit free access of the withdrawing finger 6. The same guide at the removal side of the stack is cut off above the table 12 of the machine at a distance to permit the free withdrawal of a mold. In other words the clearance between the bottom of the guiding member and the upper surface of the table 12 must at least equal the depth of a mold.

The guide 1 at the rear of the stack extends down to within a short distance of the table 12. The connecting portion of the guide terminates considerably above the table and is continued by a member 18 which may be integral or separate according to convenience in construction. This member 18 is preferably offset at 18' and disposed away from the plane of the connecting portion of the guide. The function of this is obvious when it is considered that the mold slides upon the rear guide 1 with its beveled edge resting on the connecting portion. When the beveled edge strikes the offset 18' the mold is projected to the right and the member 18 which is offset from the plane of the rest of the guide serves to project the mold out of the stack so that the notch 5 will be sure to clear the end 13 of the forward guide. It will readily be seen that the forward position of the lowermost mold may be regulated by the shape of the member 18' and the degree of offset. Preferably the member 18 is formed of resilient material. Fig-

ures 3 to 6 show the action of the member 18 which is formed of resilient material. Figures 3 and 4 show the offset 18' as the lowermost mold 3 rides up upon it. Figure 5 shows the member 18 pressed to straight position by the weight of the mold. Of course the total weight of the mold stack is exerted in part upon this member 18 at this time. Figure 6 shows the member 18' restored to rest position. As soon as the lowermost mold clears the restraining forward guide the resilient nature of the member 18 causes it to project this mold slightly beyond the guide

The cycle of feeding a mold is brought out in detail in Figures 3 to 6. In Figure 3 one of the compression molds 3 has already been carried so far out of the stack that its rear edge 15 has nearly cleared the bottom surface 16 of the overlying mold. The overlying mold is here supported upon the edge 15 of the mold being removed and at its rear edge upon the offset 18' of the member 18. When the mold 3 is removed further the condition shown in Figure 4 obtains. Here it will be seen that the overlying mold has tilted so that its forward edge lies closer to the table 12 than its rear edge. The oblique bevel 17 at the forward edge of the mold now rests upon the edge 15 of the mold being removed. In a further position of the mold being removed the beveled surface 17 rests upon the edge 19 of the mold which is now practically out of the stack. The lowest mold of the stack is now almost upon the surface of the table 12. The bottom surface 16 of this mold is still oblique and the spring member 18 is flexed to straight position. Figure 6 shows the lowermost mold after the preceding mold has been removed entirely. This mold has settled upon the table 12. The forward edge of the mold has cleared the lowest part of the forward guide and the member 18 has pushed the mold forwardly to expose the notch 5 to the feeding finger 6.

The cycle disclosed in Figures 3 to 6 illustrates the smoothness with which the molds are placed in position and fed. There is no sudden dropping and the whole operation is performed as a sliding operation. The molds do not rest with their entire weight upon each other. A good portion of the weight is borne by the rear guide which supports the rear beveled edges 2 of the molds. As the molds descend in the stack due to the removal of lower molds they are projected gradually toward the feeding position due to the beveled shape of the guides. When finally the mold reaches the position next to the last it is supported until the stepped end of the receding mold reaches the region of the beveled forward edge. In this position the beveled edge rides successively down the two steps of the preceding mold and the entire mold is slid into position on the surface of the table 12. In its final motion the mold clears the forward guide and the member 18 imparts a slight shove to it to eject it partially from the stack. If the member 18 is not made resilient the mold is partly ejected by the change in angle of the member with respect to the guide and by the weight of the overlying molds. Tobacco carried in the molds is not subjected to shocks which would produce loosening and the molds themselves are likewise protected from damage.

The details of the cigar machine and the machine for dealing with the molds after they are removed from the stack are omitted because they have no place in this invention. Likewise the details of the device for removing the lowermost mold are omitted because they are well known

and the invention which resides in the feeding of the molds is not dependent upon any particular structure for removing the lowest mold.

It is obvious that various changes and modifications may be made in the details of construction and design of the above specifically described embodiment of this invention without departing from the spirit thereof, such changes and modifications being restricted only by the scope of the following claims:

What is claimed is:

1. A device for feeding cigar compression molds to a delivery table comprising two guide members for holding the molds in stacked relation, both 15 guide members having outer flanges extending laterally with the molds and a connecting portion between said flanges, said guide members being obliquely disposed above the table to hold the superposed molds in longitudinally offset relation, the guide member at the forward ends of the molds terminating above said delivery table to permit withdrawal of the lowermost mold, said molds having notches in both the upper front and rear portions thereof, a controllable finger device positioned at the front of said feeding device to engage the said notch of the lowermost mold and thereby project the mold forward upon said delivery table, and a spring element at the base of the rear guide member to urge said lowermost mold forwardly into position where said finger device may engage the notch thereof.

2. In a delivery device, a magazine having front and rear walls inclined downwardly and forwardly in the direction of delivery of the articles, said front and rear walls adapted to cause the stack of articles in the magazine to assume a stepped relation, the front wall having a cut-away portion forming a delivery opening at its 35 lower forward portion horizontally opposite the lower inclined portion of the rear wall which is adapted to automatically guide the lowermost article toward the delivery opening, and compressible resilient means located at the lower portion of the rear wall in alignment with the descending articles adapted to be initially compressed by the articles until the lowermost article arrives opposite said delivery opening and is released from the confinement of the front wall 45 whereupon said compressed resilient means is allowed to kinetically expand and move a portion of the article through said delivery opening.

3. In a delivery device, a magazine for containing in stacked form the articles to be delivered 55 and having at a low point a delivery opening, and compressible resilient means in the magazine opposite the delivery opening positioned therein to be engaged by the descending articles in the stack and constructed and arranged to be initially compressed and put in a potential condition by the articles before reaching the delivery opening and adapted to cause the articles to be moved through the delivery opening when the articles arrive opposite such opening.

4. In a delivery device, an inclined magazine for holding a stack of articles to be delivered with the article below offset forwardly in the direction of delivery as respects the article immediately above it, said magazine having a delivery opening at the lower front portion thereof and having a rear inclined portion disposed opposite said delivery opening, and an inclined guiding element in the magazine opposite said delivery opening positioned in the path of the articles and disposed at a greater angle to the vertical than the incli-

nation of the magazine and so constructed and arranged with relation to the descending stack of articles and to said delivery opening that said guiding element is adapted to cause the lowermost article to automatically ride down the same incident to the superincumbent weight of the stack and the forward outwardly stepped portion of the lowermost article to be projected through said delivery opening, said inclined guiding element being flexible and resilient.

5. In a delivery device for molds having sockets in their upper delivery ends, an inclined mag-

azine for holding the molds in a stepped stack, said magazine having a delivery opening in its forward lower portion, operative delivery means in the magazine adapted to cause the ejection of the socketed delivery end of the lowermost mold through the delivery opening, and an arm operatively mounted above the plane of the delivery opening and having a finger extending down therefrom for engaging the socket in the delivery end of the mold for withdrawing the mold completely from the magazine.

CONSTANTIN FRIEDRICH RÖBER.
